CARRYING CASE FOR CHEMICAL TESTING EQUIPMENT OR SIMILAR ARTICLE

Granville E. Robbins, Norton, and John Newton Perham,
Middleboro, Mass., assignors to Texas Instruments Incorporated,
Dallas, Tex., a corporation of Delaware

Filed Jan. 16, 1961, Ser. No. 63,597

Term of patent 14 years

(Cl. D87—5)

Fig. 1.

Fig. 2.

Fig. 3.

Fig. 4.

Fig. 5.

Fig. 6.

FIG. 1 is a top plan view of a carrying case for chemical testing equipment or similar article showing our new design;

FIG. 2 is a left-hand side elevational view thereof;

FIG. 3 is a front elevational view thereof;

FIG. 4 is a rear elevational view thereof;

FIG. 5 is a top perspective view thereof, with the cover opened showing the interior thereof; and

FIG. 6 is a left-hand side elevational view with the cover and another part thereof opened.

Our design is characterized by a series of aligned openings on one face of the case in combination with a co-ordinately positioned opening in the opposite face thereof, all as shown.

The testing components shown in broken lines are for illustrative purposes only.

We claim:

The ornamental design for a carrying case for chemical testing equipment or similar article, substantially as shown and described.
